(57) **CLAIM**

The ornamental design for a basketball return device, as shown and described.

DESCRIPTION

FIG. 1 is a perspective view of the basketball return device design.

FIG. 2 is a front view of my inventive basketball return device.

FIG. 3 is a rear view of FIG. 2.

FIG. 4 is a side view of FIG. 2.

FIG. 5 is a top view of FIG. 2; and,

FIG. 6 is a bottom view thereof.

A second embodiment of my design consists of the configuration as shown in FIGS. 1-6 made of a transparent material. A third embodiment of my design consists of the configuration as shown in FIGS. 1-6 made with a translucent material.

The broken lines shown in FIG. 1 are included for the purpose of illustrating environmental structure and form no part of the claimed design.
